(57) **CLAIM**

The ornamental design for a driver circuit integrated LED module, as shown and described.

DESCRIPTION

FIG. 1 is a perspective view of a driver circuit integrated LED module showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a top exploded perspective view thereof;

FIG. 9 is a bottom exploded perspective view thereof; and,

FIG. 10 is a front exploded view thereof.

1 Claim, 10 Drawing Sheets
